UNITED STATES PATENT OFFICE.

LIBANUS M. TODD AND CHARLES G. TIEFEL, OF ROCHESTER, NEW YORK, ASSIGNEES, BY
MESNE ASSIGNMENTS, TO TODD PROTECTOGRAPH COMPANY, OF ROCHESTER, NEW
YORK, A CORPORATION OF NEW YORK.

ATTACHMENT FOR CHECK-PROTECTORS.

1,183,606.

Specification of Letters Patent. Patented May 16, 1916.

Application filed August 12, 1911. Serial No. 643,792.

To all whom it may concern:

Be it known that we, LIBANUS M. Todd and CHARLES G. TIEFEL, both of Rochester, in the county of Monroe and State of New York, have invented certain new and useful Improvements in Attachments for Check-Protectors; and we do hereby declare the following to be a full, clear, and exact description of the same, reference being had 10 to the accompanying drawings, forming a part of this specification, and to the reference-numerals marked thereon.

The invention has for its object to afford an improvement to be applied to machines 15 for protecting commercial paper, known commonly as check protectors, such as disclosed in Patent No. 793,249, June 27, 1905, the purpose being to afford a stamping or printing mechanism by which additional 20 data may be applied to the check, as for instance, in preparing it for certification.

A further object of the invention is to provide a simple construction that may be readily embodied in check protectors of the 25 usual types, the parts being so arranged as to effect the discharge of a check from the machine when the printing mechanism is operated.

To these and other ends the invention 30 consists in certain improvements and combinations of parts all as will be hereinafter more fully described, the novel features being pointed out in the claims at the end of the specification.

35 In the drawings: Figure 1 is a view in end elevation of a check protector of a usual type, embodying a check certifying mechanism constructed in accordance with the present invention; Fig. 2 is a similar view, 40 looking in the opposite direction; Fig. 3 is a front elevation of the certifying mechanism; Fig. 4 is a sectional view on the line $x-x$ of Fig. 3; Fig. 5 is a vertical sectional view, taken centrally of Fig. 3; Fig. 6 is a 45 vertical sectional view on the line $y-y$ of Fig. 5; Fig. 7 is a detail perspective view of the rotary member which supports the ink supplying pad and printing surface; Fig. 8 is a detail sectional view taken through a 50 portion of the rotary member, and showing one pair of adjustable dies, and Fig. 9 is a sectional view on the line $a-a$ of Fig. 8; Fig. 10 is a face view of the dies of the rotary printing member.

Similar reference numerals throughout 55 the several figures indicate the same parts.

The invention contemplates effecting two operations in one machine, that is to say, marking a check to protect it against being raised, and also printing or stamping upon 60 the check any additional data that may be desired, as for instance in preparing a check for certification, the parts being so combined as to afford a common support for the check, both for the marking mechanism and for 65 the printing mechanism, and to eject the check from the machine by the operation of the printing mechanism.

The invention may be variously adopted 70 in connection with any form of check protector, and in the present embodiment, which shows a preferred form, the check protector is of the usual type, and comprises the casing 1 containing the operating mechanism for marking the check with the limiting amount, 75 movement of the parts within the casing 1 being obtained by the lever 2 in the usual manner. The printing mechanism may be combined with the marking mechanism in any suitable manner, and in the present embodiment, comprises the casing 3 secured to the end of the casing 1, as shown in Figs. 1 and 2. The casing 3 contains the devices for stamping the check for certification, the latter being inclosed within the casing 3 by 80 the end plate 4 suitably attached to the latter.

The printing devices, previously referred to, preferably include the rotary member 5 which is journaled upon the bearing 6, the 90 latter being carried by the casing 3. The rotary member 5 is preferably constructed as shown in Fig. 7 with the projection 7 having outwardly projecting flanges 8 and a series of lugs 9 disposed oppositely to the 95 projection 7, and separated by the transversely arranged recesses 10. The extreme or end lugs 9 are provided with inwardly extending flanges or ribs 11, the lugs all being recessed or slotted centrally, as indicated at 12. The ink supplying pad is carried by the rotary member 5, and preferably comprises a series of adjacently positioned layers 13 of felt, or other similar absorbent material, these being formed so as to engage the flanges 8 upon the projection 7, and the ribs 11, as shown clearly in Fig. 5, whereby they are held securely on the rotary member,

the periphery of the pad being preferably rounded, for coöperation with an ink transferring roll, designated at 14. The roll 14 is mounted on the pivoted arms 15 suitably 5 journaled in the casing 3, said arms being engaged by the spring 16 whereby to cause the transferring roll 14 normally to engage the inking pad on the rotary member 5. The transferring roll 14 engages the printing 10 surface carried by the rotary member 5, which preferably includes a series of circular dies 17 arranged in pairs transversely of the rotary member 5, in the recesses 10. The circular dies are provided with central openings 15 adapted to be engaged by the arc shaped support 18, positioned in the cutaway portions 12, and preferably held in place by set screws 19. The circular dies 17 are provided with the various characters necessary for 20 stamping the proper day, month and year upon the check, and are held in their adjusted positions in any suitable manner, and preferably, as in the present embodiment, by means of the spring plates 20 which are 25 mounted on the support 18 and held in locking relation with the dies by means of shoulders 21 which engage the cut-away portions 12. The locking plates are provided with projections 22 struck therefrom, and arranged to engage the depressions 23 formed 30 in the adjacent surfaces of the dies. The parts are so related that the spring plates 20 engage the printing dies with sufficient force to hold the latter normally against turning, 35 but are sufficiently yieldable to permit the dies to be moved for adjustment when necessary. A stationary die 24 is suitably mounted on the rotary member 5 and is provided with the data that it is desired to 40 print upon the checks, said stationary die having suitable openings to receive the printing surfaces of the adjustable dies already described. The rotary member 5 is preferably provided with the crank 25 and 45 handle 26, by which the printing mechanism is operated. Access may be had to the interior of the casing 3, for adjusting the movable printing dies, by means of the hinged cover 27 which is held normally in 50 closed position by frictional engagement with the casing.

The check is held in position for marking by means of the supporting plate 28 which is suitably secured to the casing 1, and is 55 provided with the extension 29 projecting beyond the casing 1 and underneath the casing 3, and provided with an opening for a purpose now to be mentioned. Pivotedly mounted on the extension 29 is the 60 arm 30 within which is journaled the roll 31 arranged to project through the opening in the supporting plate, and to support a check while the latter is engaged by the printing surface. The roll 31 is held in 65 yieldable engagement with the printing sur-

face by means of a spring 32 surrounding the post 33 and arranged between a head 34 on said post and the recessed portion 35 of the arm 30.

In the operation of the parts, the check 70 being in normal position upon the supporting plate 28, after the operation of the marking or protecting devices, the handle 26 is moved from its lowered position, shown in Fig. 6, forwardly, upwardly and 75 rearwardly until it has made a complete revolution, causing the printing surface on the rotary member 5 to be brought into engagement with the check, whereby the latter is stamped for certification. The printing 80 surface is inked at each revolution by means of the transferring roll 14, which is fed from the ink supplying pad on the rotary member. By reason of the rotary movement of the printing surface, and the engagement 85 of the latter with the roller 31, the check is gripped as it is printed, and discharged from the machine upon disengagement of the printing surface.

We claim as our invention:

1. The combination with a check protector, 90 of a certifying mechanism carried thereby and comprising a rotary member, an inking pad carried thereby, a printing surface carried by the rotary member, an ink transferring roll adapted for engagement with the printing surface and inking pad, a check supporting plate carried by the protector and extending beneath the certifying mechanism, and a roll yieldably supported on 95 said plate and adapted to engage the printing surface.

2. The combination with a marking mechanism for protecting a check, of a supplemental printing mechanism carried thereby 100 and including a rotary member, an arc-shaped support on the rotary member, a series of radially disposed dies adjustably mounted on the support, supporting means for a check disposed adjacent to the marking mechanism and extending under the printing mechanism, the operation of the printing mechanism serving to eject a check 105 from the machine.

3. The combination with a marking mechanism for protecting a check, of a supplemental printing mechanism carried thereby 110 and comprising a rotary member, a supporting rod arranged on the rotary member and extending circularly with respect to the axis thereof, and a series of dies adjustably mounted on the supporting rod and disposed radially of the rotary member, the operation 115 of the printing mechanism serving to eject a check from the machine.

4. The combination with a marking mechanism for protecting a check comprising a plurality of types movable, selectively, to 120 printing position; and a platen common to said types, said platen and types having a 125

relative movement toward and from each other to impress the work; of a supplemental printing mechanism comprising a rotary carrier provided with a plurality of types 5 adjustable thereon; a platen roller for co-operation with said carrier; and means for rotating said carrier and roller in contact with each other and thereby simultaneously printing the work and ejecting it from the machine.

5. The combination with a frame having a work supporting plate and a casing overhanging said plate; a type carrier in said casing provided with a plurality of types, 15 said types being movable, selectively, to

printing position; a platen below the plate common to said types, said types and platen having a relative printing movement; of a rotary carrier above the plate provided with a plurality of types adjustably mounted 20 thereon; and a platen roll below the plate, said rotary carrier and platen roll being adapted to be rotated in contact with each other to thereby print the work and eject it from said slot.
